CIRCUIT INTERRUPTER

Herbert L. Rawlins, deceased, late of Pittsburgh, Pa., by Charlotte M. Rawlins, administratrix, Pittsburgh, Pa., assignor to Westinghouse Electric Corporation, East Pittsburgh, Pa.; a corporation of Pennsylvania

Application August 12, 1950, Serial No. 179,066.

6 Claims. (Cl. 200—144)

1

This invention relates to circuit interrupters in general, and more specifically to arc-extinguishing structures therefor.

A general object of the invention is to provide an improved circuit interrupter having an improved arc-extinguishing structure, which will more effectively interrupt the circuit therethrough than has heretofore been achieved.

A more specific object is to provide an improved circuit interrupter, particularly one of the air-break magnetic type, in which a restriction is purposely interposed between the contact chamber and the arcing chamber so that the interruptions will generally all be of one type, i. e., will take place at about the same point in the current wave.

Still a further object is to improve the spaced insulated plate type of arc chute in an air-break magnetic circuit interrupter by utilizing a pair of cooperating plate members spaced laterally apart and affording a restriction to the upward movement of the arc from the contact chamber or region past the cooperating plates into the upper arc chute chamber, wherein arc extinction takes place.

Still another object is to provide an improved circuit interrupter in which the arc is momentarily held against a normally insulating surface which has an inverse temperature-resistance characteristic. In other words, when such a material is heated by the arc its resistance drops, and the result is the same as having a resistance across the arc horns which damps the high frequency transients present at interruption to effect more efficient arc extinction.

Further objects and advantages will readily become apparent upon reading the following specification, taken in conjunction with the drawings, in which:

Figure 1 is a side elevational view, partially in vertical section, of an air-break magnetic type circuit interrupter embodying my invention and shown in the closed circuit position;

Fig. 2 is a vertical sectional view taken substantially along the line II—II of Fig. 1, looking in the direction of the arrows; and

Fig. 3 is a side elevational view of one of the plate details utilized in the arc chute of Fig. 1.

Referring to the drawings, and more particularly to Fig. 1 thereof, the reference character 1, generally designates contact structure operable to draw an arc which moves upwardly into an interrupting chamber, generally designated by the reference numeral 2. The arc is interrupted within the interrupting chamber 2 to thereby interrupt the circuit controlled by the breaker.

2

More specifically, the contact structure 1 includes a terminal stud 3 surrounded by a flanged insulating bushing 4, the latter extending through a support plate 5 and secured thereto. At the right-hand end of the terminal stud 3 is secured a stationary main contact 6 having a pair of outwardly extending metallic support plates 7 secured thereto. A rotatable contact arm 8 is pivotally mounted at 9 between the support plates 7, and is caused to move thereabout by the actuation of an insulating operating rod 12.

The operating rod 12 is actuated by suitable mechanism, not shown, but which is responsive either to manual operation or to the existence of overload conditions existing in the circuit controlled by the interrupter.

The operating rod 12 is pivotally connected at 13 between a pair of support plates 14 rigidly secured to and rotatable with the contact arm 8.

Also movable with the contact arm 8 is a main contact bridge 15 formed of conducting material and electrically interconnecting the stationary main contact 6 with a second stationary main contact 17. The contact 17 is secured to the right-hand end of a second terminal stud 18, which is likewise enclosed within a flanged insulating bushing 19. The bushing 19 is secured to and supported by the framework or supporting plate structure 5.

Movable with the rotatable contact arm 8 is a piston cylinder 20 within which moves a piston, not shown, secured to a piston rod 21, pivotally secured at 22 to the support plates 7.

It will be apparent that upon clockwise opening rotative motion of the contact arm 8 about the pivot point 9, the piston, not shown, will move upwardly within the piston cylinder 20 to force a blast of compressed air out of the upper end of the piston cylinder 20 and through a blast tube 23 adjacent the contact structure. This blast of air facilitates upward movement of low current arcs into the interrupting chamber 2 when, because of the low currents involved, the magnetic field is relatively weak.

The piston construction is set forth and claimed in United States Patent 2,491,964, issued December 20, 1949, to Russell E. Frink and assigned to the assignee of the instant application.

Also supported by the second stationary main contact structure 17 are a pair of relatively stationary secondary and arcing contacts respectively designated by the reference characters 24, 25. The secondary contact 24 cooperates with a movable secondary contact 26 carried by the contact arm 8. The construction is such that the

movable secondary contact 26 separates from the relatively stationary secondary contact 24 after disengagement of the contact bridge 15 from the stationary main contacts 6, 17. However, the secondary contacts 24, 26 separate prior to the separation of the arcing contacts 25, 27. Thus, the arc which is finally drawn by operation of the contact structure 1 is drawn between the arcing contacts 25, 27.

Because of the loop circuit formed by the contact structure 1 including the horizontally disposed terminal studs 3, 18 and the moving arm 8, the arc which is finally drawn between the arcing contacts 25, 27 expands upwardly to thereby cause one portion of the drawn arc to engage the panel arcing horn or arc terminal member 30. The arc position at this point is indicated by the dotted line 32 with the movable arcing contact 27 being moved to the position shown in dot-dash lines in Fig. 1.

There is provided suitable coil structure 33, including a pair of parallel disposed blowout coils 34. One end of the coils 34 is connected to the socket stationary contact 35. The other end of the coils 34 is connected to the stationary main contact structure 17 by the strap connection 34a.

Thus upon transfer of one terminal of the arc 32 to the arcing horn 30, the coil structure 33 will be inserted into series circuit and will serve to energize the transverse magnetic field extending between the magnet pole shoes 36, 37. This transverse magnetic field extending across the interrupting chamber 2 serves to cause upward movement of the arc, now designated by the reference character 38, into the arc chute 39 including a plurality of spaced slotted ceramic plates 40.

It will be noted that each pole shoe 36, 37 has depending downwardly therefrom and secured thereto, such as by welding, a sub-pole piece 42.

The use of such sub-pole pieces 42 facilitates the initial upward movement of the arc initially drawn between the contacts 25, 27. This follows inasmuch as when the arc is originally drawn between the arcing contacts 25, 27 there is formed a magnetic field about said arc. A portion of the magnetic field passes through the sub-pole pieces 42 through the pole shoes 36, 37 and through the core 43 enclosed by the blowout coils 34. However, the magnetic field below the arc, as initially drawn between the arcing contacts 25, 27, must pass through the air space below the arc and since the magnetic field is more concentrated below the arc than above it, the arc is rapidly moved upwardly to cause a portion of it to strike the arcing horn 30. Also the portion of the arc, designated by the reference numeral 44, is moved toward the left into the transfer interrupting stack generally designated by the reference numeral 47. It will be noted that the transfer interrupting stack 47 includes a plurality of spaced slotted ceramic plates 48 having slots 49 provided therein.

A transfer arc horn 54 is made of metallic material. Below the arcing horn 54 and secured thereto by rivets are a plurality of plates formed of magnetic material, such as steel. In this instance, there are four such magnetic plates, two of which are designated by the reference character 59 and two of which are designated by the reference character 60. The presence of the four plates 59, 60 of magnetic material disposed immediately below the transfer arc horn 54 facilitates the leftward movement of the lower end of

the arc from the stationary arcing contact 25 to the arc horn 54 and also facilitates the entering motion of the arc portion 44 of the arc 32 into the transfer interrupting device 47. The position of the arc portion 44 may now be designated 44a.

High field strengths have been found necessary for high interrupting capacity within a small space. All of the flux across the interrupting chamber 2 between the pole shoes 36, 37 must thread the magnetic coils 34. This means that the reactance of the magnetic coils 34 is high, and a countervoltage of several hundred volts will appear across the terminals of the magnetic coils 34 when the short circuit current is attempted to be transferred to the coils 34, which are in parallel, and which are connected electrically between the arc horn 30 and the upper terminal stud 18.

This makes the transfer interrupter 47 necessary to interrupt the arc portion 44a extending between the transfer arc horn 54 and the arc horn 30.

The use of a transfer interrupting device 47 to facilitate insertion into series circuit of the blowout coils 34 is more fully set forth and claimed in U. S. patent application filed January 4, 1947, Serial No. 720,165 by Robert C. Dickinson and Russell E. Frink and assigned to the assignee of the instant application. This application also sets forth and claims the use of the sub-pole pieces 42 to facilitate the initial upward movement of the arc as initially drawn between the arcing contacts 25, 27.

After the transfer interrupting device 47 has interrupted the arc portion 44a and caused the arc to extend between the arc horn 30 and the movable arcing contact 27, the parallel disposed blowout coils 34 are in series circuit, and energize the transverse magnetic field extending across the interrupting chamber 2 through the pole shoes 36, 37. The right-hand end of the arc 32 soon transfers to the right-hand arc horn or arc terminal member 62, which is connected by a conducting strap 63 to the lower terminal stud 3 of the interrupter. Thus the reference character 38 indicates the position of the arc extending between the arc horns 30, 62 after the blowout coils 34 are in series circuit.

The arc 38 is moved upwardly within the arc chute 39, which, as mentioned previously, includes a plurality of spaced insulating ceramic plates 40. Fig. 3 more clearly shows the configuration of the plates 40.

It will be noted that each plate 40 has a slot 64 provided therein, the upper closed end of which is slightly unsymmetrical about the center line 65 of the plate 40. Thus the alternate positioning of the plates 40 about the center line 65 of said plates produces a zig-zag arc passage 66 at the upper closed ends of the staggered slots 64.

The upward movement of the arc 38 into the arc chute 39 and into the upper closed ends of the slots 64 effects the restriction thereof and also the elongation thereof. The transverse magnetic field extending between the pole shoes 36, 37 imparts to the electrons an upward component of velocity. These electrons bombard gas particles and produce an actual blast of gas perpendicular to the arc, which action requires the arc to ionize fresh quantities of gas in considerable quantities. When current zero is reached, this action is continued to effectively deionize the arc and establish dielectric in the arc chute 39. The theory of the interrupting operation is more clearly set forth in U. S. Patent 2,442,199, issued May 25,

1948, to Robert C. Dickinson and Russell E. Frink and assigned to the assignee of the instant application. Certain features of the foregoing arc chute are described and claimed in United States patent application filed January 4, 1947, Serial No. 720,166, by Herbert L. Rawlins, Robert C. Dickinson, and Russell E. Frink and assigned to the assignee of the instant application.

This invention is particularly concerned with an improved method of arc control for high voltage air circuit breakers of the magnetic blowout type. Improvement in operation of circuit-breakers of this type could be obtained if it were practical to make the arc always enter the arc chute 39 or arc passage 66 at the same time with respect to current zero. Various schemes have been devised to time the opening of the contacts to accomplish this, but they have been too complicated to be commercially practical. It is readily apparent, moreover, that the problem is rendered more difficult in a three-pole, single mechanism breaker. In such a breaker the contacts open at the same time, but the value of the instantaneous current is different in each of the three poles. Thus, current zeros fall at different times in the three phases.

A structure has been devised which accomplishes timing of the entrance of the arc 38 into the arc chute 39 or arc passage 66 independently of the time of contact parting. As will be apparent from the following description, the device is simple and adds little to the cost of the interrupter. Furthermore, tests show that the desired results are accomplished. This permits the field strength, slot shape, etc., to be coordinated in such a manner that the interrupter will work best on the one type of interruption that will result. Otherwise, it is necessary to produce a compromise design which will handle many types of interruption and, therefore, is less efficient.

Referring particularly to Fig. 2, it will be observed that there are provided a pair of converging refractory arc shields 67, 68. A pair of horizontally disposed rectangular pieces 69, 70 of refractory insulating material, preferably ceramic, are placed between the arc shields 67, 68 and the arc chute 39. Consequently, there is formed a narrow, slot-like opening or aperture, designated by the reference character 72, and dividing the arc chute into a lower contact chamber or region 74 and an upper arc chute chamber or arcing chamber 66. Fig. 2 approximately shows the critical proportions utilized in a test sample. The slot 72 was $\frac{3}{8}$ inch wide, and the distance S was $1\frac{1}{8}$ inch.

Circuit interruption with the foregoing device takes place as follows. The arc, which is drawn between the arcing contacts 25, 27, transfers to the arc horns 30, 62 in the manner previously described, energizing the magnetic structure 33. The transverse magnetic field, extending between the pole shoes 36, 37, forces the arc 38 into the upper part of the lower chamber 74 against the refractory pieces 69, 70. The narrow slot-like aperture 72 between the pieces 69, 70 permits only a fraction of the ionized gas to pass into the relatively cool upper chamber 66 where the deionization is sufficient to keep the ion density below that in the lower chamber 74 as long as the current in the arc stream 38 is high. When current zero is approached, the ionization of fresh quantities of gas in the lower chamber 74 practically ceases, and the momentum of the gas upwardly through the aperture 72 into the upper chamber or arc passage 66 carries enough of the

residual ionization up that when the current re-establishes in the opposite direction, the ionization in the upper chamber 66 is more intense than in the lower chamber 74, and the arc 38 is re-ignited in the upper arcing chamber 66.

The magnetic field now carries the arc 38 rapidly to the tops of the slots 64, while it is still small, and the high resistance due to restriction and length limits the current passing through the arc stream 38 to a fraction of the value it would reach without the interrupter. The greatly reduced amperage and high power factor caused by this sequence of events makes interruption easy, and this occurs at the next current zero.

The spaced insulating plate portions 40 are particularly effective, in conjunction with the transverse magnetic field set up by the coil structure 33, to effect the extinction of low current arcs. This is particularly important since, unlike previous structures of this type, the plate portions 40 are only called upon to interrupt relatively low current arcs. Moreover, the freely-vented exhaust passages 45 provided between the several plates 40 bring particularly effective deionizing conditions to bear upon the low current arc 38 after it has passed above the restricting pieces 69, 70 into the arc passage 66.

Thus, the combination of the slot 72 and the arc chute 39, particularly designed for low current interruption, together with the transverse magnetic field, all contribute to result in a circuit interrupter particularly effective in operation.

Still another advantage is obtained with the structure described. The pieces 69, 70 placed across the arc chute and heated to a high temperature by confining the arc 38 in the lower chamber 74 may be made to act as a resistor and damp the high frequency transients present at interruption. However, an instant later, after the arc 38 has moved above the pieces 69, 70 and has been extinguished in the arc chute 39, these pieces 69, 70 will have cooled sufficiently to present practically infinite resistance to the circuit. Thus, means may be provided for momentarily holding an arc against a normally insulating surface which has an inverse temperature characteristic (drops to 10,000 ohms at temperatures above 500° C.) and which is effectively connected across the terminals of the breaker during interruption.

From the foregoing description of the improved interrupting device, it will be apparent that there is provided improved means for controlling the entrance time of high current arcs into an arc chute. In addition, it will be apparent that there is provided improved means for damping the high frequency transients present at interruption by utilizing a normally insulating piece of material connected across the terminals of the breaker having an inverse temperature-resistance characteristic. The normally insulating piece of material, whose resistance value drops at relatively high temperatures, brings about a situation in which a high resistance is connected between the terminals of the breaker at the time of interruption, thereby damping the high frequency transients present at the time of interruption. The theory of such transient effects, at the time of interruption, are set forth in detail in United States Patent 2,467,760 issued April 19, 1949, to Leon R. Ludwig, Benjamin P. Baker and Winthrop M. Leeds, and assigned to the assignee of the instant application.

Although there is shown and described a

specific structure, it is to be clearly understood that the same was merely for the purpose of illustration, and that changes and modifications may readily be made therein by those skilled in the art, without departing from the spirit and scope of the appended claims.

What is claimed as the invention is:

1. A circuit interrupter including means for establishing an arc, an arc chute for extinguishing the arc, restricting means disposed within the arc chute dividing it into a contact chamber and an arc-extinguishing chamber, the restricting means causing the arc to enter the arc-extinguishing chamber only near the current zero period, and the restricting means being composed of insulating material having an inverse temperature-resistance characteristic and effectively connected across the terminals of the interrupter to damp the high frequency transient voltage at the time of interruption.

2. A circuit interrupter including means for establishing an arc, an arc chute for extinguishing the arc, insulating material bridging the terminals of the arc chute against which the arc is momentarily forced, and the insulating material having an inverse temperature-resistance characteristic to damp the high frequency transient voltage at the time of interruption.

3. A circuit interrupter of the air-break type including means for establishing an arc, an arc chute for extinguishing the arc, restricting means disposed within the arc chute dividing it into a contact chamber and an arc-extinguishing chamber, the arc-extinguishing chamber comprising a plurality of spaced insulating plate portions, means for establishing a transverse magnetic field for moving the arc against the insulating plate portions, and the restricting means causing the arc to enter the arc-extinguishing chamber only near the current zero period.

4. A circuit interrupter of the air-break type including means for establishing an arc, an arc chute for extinguishing the arc, restricting means disposed within the arc chute dividing it into a contact chamber and an arc-extinguishing chamber, the arc-extinguishing chamber comprising a plurality of spaced insulating plate portions, means for establishing a transverse magnetic field for moving the arc against the insulating plate portions, the restricting means causing the arc to enter the arc-extinguishing chamber only near the current zero period, and the restricting means being composed of insulating material having an inverse temperature-re-

sistance characteristic and effectively connected across the terminals of the interrupter to damp the high frequency transient voltage at the time of interruption.

5. A circuit interrupter of the air-break type including means for establishing an arc, an arc chute for extinguishing the arc, a pair of co-operating elongated insulating members closely spaced apart to afford a restriction dividing the arc chute into a contact chamber and an arc-extinguishing chamber, the arc-extinguishing chamber comprising a plurality of spaced insulating plate portions having freely vented passages therebetween, means for establishing a transverse magnetic field across the arc-extinguishing chamber for moving the arc therein against the insulating plate portions, and the closely spaced apart members permitting the arc to enter the arc-extinguishing chamber only near the current zero period.

10 6. A circuit interrupter of the air-break type including means for establishing an arc, an arc chute for extinguishing the arc, a pair of co-operating elongated insulating members closely spaced apart to afford a restriction dividing the arc chute into a contact chamber and an arc-extinguishing chamber, the arc-extinguishing chamber comprising a plurality of spaced insulating plate portions having freely vented passages therebetween, means for establishing a transverse magnetic field across the arc-extinguishing chamber for moving the arc therein against the insulating plate portions, the closely spaced apart members permitting the arc to enter the arc-extinguishing chamber only near the current zero period, and the closely spaced apart members being of insulating material having an inverse temperature-resistance characteristic and effectively connected across the terminals of the interrupter to damp the high frequency transient voltage at the time of interruption.

CHARLOTTE M. RAWLINS,
Administratrix of the Estate of Herbert L.
Rawlins, Deceased.
